UNITED STATES PATENT OFFICE.

CHARLES H. GAIL, OF CINCINNATI, OHIO, ASSIGNOR TO THE SHOTT MANUFACTURING COMPANY, OF CINCINNATI, OHIO, A CORPORATION OF OHIO.

BED-SPRING.

1,387,150.

Specification of Letters Patent. Patented Aug. 9, 1921.

Application filed April 22, 1921. Serial No. 463,633.

To all whom it may concern:

Be it known that I, CHARLES H. GAIL, a citizen of the United States, residing at Cincinnati, in the county of Hamilton and State 5 of Ohio, have invented certain new and useful Improvements in Bed-Springs, of which the following is a specification.

The present invention is designed to provide simple and efficient means for yieldingly securing together the top coils or convolutions of the upright spiral springs of bed-springs and similar structures, whereby the bed-spring or other structure as a whole 10 will possess marked resilient or cushioning 15 capabilities.

It is not broadly new to fasten the upper coils of such spiral springs together by means of short helical or coiled springs, but one leading purpose of the present invention 20 is the fastening or securing of the ends of such intermediate or connecting helical springs to the upper coils of the vertical spiral springs in such manner that they cannot shift position under ordinary usage, that 25 the structure will be wholly noiseless, and that the top coils will not need to be crimped or deformed to hold the helical springs firmly in place.

A further purpose of the invention is the 30 production or provision of an appliance of this kind having a relatively smooth flat top surface so constructed that the superposed mattress will not sag or be depressed unduly into or between the several springs of 35 which the structure is composed.

In its preferred embodiment, the invention takes the form of structure illustrated in the accompanying drawing in the two views of which like reference characters have been 40 used to designate the same parts.

In this drawing:

Figure 1 is a fragmentary or partial plan view of a small portion only of the complete cushion spring but sufficient of the construction has been shown for the needs of this 45 patent application; and

Fig. 2 is an enlarged cross-section on line 2—2 of Fig. 1, the parts being viewed in the direction indicated by the arrows.

The improved and novel bed-spring, the 50 principles of construction of which may be advantageously employed in many other relations where cushion structures of this general type are desired, comprises, as will 55 be readily seen from the drawing, a plurality

of suitably-supported, vertical, spaced spiral or hour-glass springs 10 of which little more than the top coils or convolutions 11 are shown.

It is, of course, necessary to tie or secure 60 these top coils together to maintain the springs at all times in proper position and this is preferably done by employing elastic or expansible and contractible helical springs arranged horizontally between such upper 65 most coils, thus giving the latter adequate freedom of movement without undue or permanent displacement.

To this end, the upper coil of each spiral spring, except the marginal or border ones, 70 not illustrated, is connected to the corresponding coils of the four adjacent springs by that number of horizontal, helical springs 12, 13, 14 and 15 arranged ninety degrees apart with the springs 12 and 14 diametrically opposite one another and the remaining 75 springs 13 and 15 similarly disposed.

The loops 16 of the springs 12 and 14, formed by properly bending the end portions of the wires of which the springs are made, 80 project inwardly over and rest on the wire forming the top coil of the spiral-spring under consideration, and such loops or eyes are securely fastened in position by a cross-wire 17 extended across the middle of the top 85 coil, each end being bent to pass down through the loop at 18 inside of the top coil, then outwardly at 19 beneath the wire constituting such top coil, then upwardly at 20 through the loop outside of the top coil, 90 then over one side of the loop at 21, and then down over the side of such portion of the loop at 22.

By this simple means, these ends of the 95 two oppositely-disposed springs are so securely and firmly fastened to the spiral-spring that unintentional dislodgment or displacement is impossible even though the wire forming the top coil is not crimped at these points of attachment.

It will be observed that the end of each helical spring is held securely against the upwardly-extended part 20 of the fastening wire and that the latter is firmly held against the outer side of the top coil by reason of the section 18 of the wire which bears against the end of the loop, whereby the loop is very firmly and fixedly gripped to the top coil.

In like manner the other pair of springs 13 and 15 are fastened to the top coil of the 110

same spiral-spring by means of similarly bent ends of another wire 23 crossing such top coil at right angles to and either above or below the wire 17.

5 The other ends of each of these four helical springs are in like fashion secured to the coils of the four adjoining or neighboring spiral-springs, it being understood that each of the latter is connected to four other 10 springs in the manner indicated.

The crossing wires 17 and 23 of each upright spring not only afford means for securing or tying the helical springs in position but they also act as mattress supporting 15 means preventing the mattress from unduly sagging into the spring.

The improved and novel structure illustrated and described affords a desirable cushion or bed-spring with suitable resili- 20 ent and elastic capabilities and functions, which is comparatively simple in structure, the elements of which may be quickly and readily placed in position and assembled, and which is free from noise when in use, 25 the helical springs being so immovably clamped to the spiral-springs that slipping or sliding out of place is out of the question.

Many minor mechanical changes may be incorporated in the construction detailed 30 above and still the latter would embody the invention as presented in the appended claims, because the invention is susceptible of embodiment in a variety of forms all containing the fundamental principles of 35 structure and function on which the invention rests.

I claim:-

1. In a bed-spring, the combination of an upright spiral-spring, a horizontal helical- 40 spring having an end loop overlying the top coil of said spiral-spring, and a wire having a portion bent down through said loop inside of said top coil, then passing beneath the wire forming said top coil, then extend-

ing upwardly through said loop, then over 45 the top of one side of said loop, and then down over the side of the loop.

2. In a bed-spring, the combination of an upright spiral-spring, a horizontal helical-spring having an end loop overlying the 50 top coil of said spiral-spring, and a wire extended across said top coil and having a portion bent down through said loop inside of said top coil, then passing beneath the wire forming said top coil, then extending 55 upwardly through said loop outside of said top coil, then over the top of one side of said loop, and then down over the side of said side of the loop.

3. In a bed-spring, the combination of an 60 upright spiral-spring, a pair of horizontal helical-springs arranged outside of and at diametrically opposite points of the top coil of said spiral-spring, each of said helical-springs having an end loop overlying the 65 wire forming said top coil, and a wire ex- tended across said top coil between said helical-springs and having each end bent to attach the corresponding helical-spring to 70 said top coil, each of such bent portions 75 extending down through the loop of the spring inside of said top coil, beneath the wire forming said top coil, up through the loop outside of said top coil, over the top of one side of such loop, and down over the side of said side of the loop.

4. In a bed-spring, the combination of an upright spiral-spring, a horizontal helical-spring having an end loop extended across the wire forming the top coil of said spiral- 80 spring, and a fastening wire projecting through said loop inside of said top coil, then across the wire forming said top coil on the side opposite said loop, then through said loop outside of said top coil, and then 85 around the wire forming one side of said loop.

CHARLES H. GAIL.
